UNITED STATES PATENT OFFICE

153,051

DESIGN FOR AN ELECTRICAL CONTROL
CABINET

William G. Waggoner, Stamford, Conn., assignor,
by mesne assignments, to The Trumbull Electric
Manufacturing Company, a corporation of
Connecticut

Application July 12, 1947, Serial No. 140,246

Term of patent 14 years

(Cl. D26—5)

To all whom it may concern:

Be it known that I, William G. Waggoner, a citizen of the United States, residing at Stamford, in the county of Fairfield, State of Connecticut, have invented a new, original, and ornamental Design for an Electrical Control Cabinet, of which the following is a specification, reference being had to the accompanying drawing, forming a part thereof.

In the accompanying drawing Fig. 1 shows a perspective view of my new design for an electrical control cabinet; and Fig. 2 is an enlarged detail end elevational view of the fluted elements of Fig. 1.

Fig. 3 is an enlarged fragmentary detail end view in elevation of the upper front corner of the cabinet of Fig. 1.

Fig. 4 is an enlarged fragmentary detail end view in elevation of the lower front corner of the cabinet of Fig. 1.

What I claim is:

The ornamental design for an electrical control cabinet, substantially as shown and described.

WILLIAM G. WAGGONER.
